POWERED FOOD CART

Bruce B. Blickman, Englewood, N.J., assignor to S. Blickman, Inc., Weehawken, N.J., a corporation of New York

Application August 7, 1957, Serial No. 47,253

Term of patent 14 years

(Cl. D14—3)

FIG. 1.

FIG. 2.

FIG. 3.

FIG. 4.

I claim:

The ornamental design for a powered food cart, substantially as shown.
